UNITED STATES PATENT OFFICE.

CHARLES T. SMITH, OF CLEVELAND, OHIO, ASSIGNOR TO THE UNION ELECTRIC COMPANY, OF SAME PLACE.

PNEUMATIC HAND-DRILL.

SPECIFICATION forming part of Letters Patent No. 634,071, dated October 3, 1899.

Application filed March 16, 1899. Serial No. 709,314. (No model.)

To all whom it may concern:

Be it known that I, CHARLES T. SMITH, a citizen of the United States, residing at Cleveland, in the county of Cuyahoga and State of Ohio, have invented certain new and useful Improvements in Pneumatic Hand-Drills; and I do declare that the following is a full, clear, and exact description of the invention, which will enable others skilled in the art to 10 which it appertains to make and use the same.

My invention relates to pneumatic hand-drills; and the invention consists in the construction substantially as shown and described, and particularly pointed out in the 15 claims.

In the accompanying drawings, Figure 1 is a vertical central sectional elevation of one form of drill embodying my invention. Fig. 2, Sheet 2, is an elevation of the same drill, 20 partly in section and at right angles to Fig. 1. Fig. 3 is a perspective view of a set of connected blades, and Fig. 4 is a cross-section of one of said blades, all being alike in construction. Fig. 5 is an elevation of a modified 25 form of drill, as hereinafter fully described.

In Figs. 1 and 2, A represents the body of the drill, formed with a cylindrical motor-chamber, containing the motor-wheel C. The said body is provided with a number of features essential to the operation of the drill, 30 consisting, first, of a base or pedestal 2, on which it rests when in operation, and oppositely at its top it has a socket 3, in which is fixed a threaded stem B, sleeved upon the adjusting feed-cone D, having handles d to 35 turn the cone. As the drill engages in its work the cone is rotated by means of said handles to keep the drill at work.

At opposite sides the body A has handle- 40 sockets 4 and 5, in which are firmly fixed the handles E and F. The handle E thoroughly closes its socket; so that there is no opening therein, while the handle F is tubular and is itself sleeved upon a tube or pipe G, threaded 45 and fixed in the socket 5. A still further feature of the body A is its inlet a at the base of socket 5 into the motor-chamber and its outlet or exhaust a' through the opposite socket-base 4 and thence out through the muffed 50 openings a², an extension or enlargement be-

ing formed on the body A to provide this outlet in the form shown.

Separate heads H and H', Fig. 2, are provided for the body A, and the motor-shaft J passes through head H and has a closed bearing in the opposite head H'. A pinion K is fixed on the exposed end of shaft J outside head H, and the shaft is engaged to rotate with the motor-cylinder C by the rods c, which connect the several sets of blades L. 55 The part C is cylindrical, as shown, but relatively smaller than the chamber in which it works, so as to leave a space for the application of the motive fluid, which preferably is compressed air, and the said hub is set at 60 one side of the axis of the said chamber to get the desired operation of the blades L, as is now common.

Four several blades L are shown, connected in pairs oppositely, and each blade has its 70 bearing in an open slot or channel extending the full length of the hub. These blades necessarily fit closely at their sides in the correspondingly flat sides of the slot and are deep enough in the slot when farthest out to 75 give a firm bearing on both sides. Two things necessarily occur with all the blades as they come successively into action—viz., they carry the full pressure of the motive agent against one side, while they also slide upon the side 80 walls of the slots forming their bearings. Experience has demonstrated that in this operation of the blades, with metal upon metal, a great deal of friction is unavoidable, and incident rapid wear upon the blades as well 85 as upon the sides of the slots or channels in which they are located, however much precaution may be taken to lubricate the blades and preserve them intact, occasions a rapid wearing out of the blades. I have therefore 90 overcome this objection and presented the trade with a much superior construction by means of a blade of fiber or leatheroid. Both of these elements have exceptional wearing quality and require but little lubricating to 95 render them serviceable for a practically indefinite period and without injury to the cylinder. Blades thus constructed and associated also preserve a smooth wearing-surface, which is improved by use, and so far as I 100

know are an original and novel discovery and invention in this art.

A further feature of novelty is the substantially Y-shaped metallic strip *c'*, set 5 lengthwise in the edge of each blade and having a substantially V-shaped trough. In this trough I place a separate loose, more or less, compact strip *N*, rounded in cross-section on bottom and side and substantially 10 flat across its top. The flat top bears against the wall of the chamber, making a close packing or bearing strip for the blade, while the rounded bottom affords freedom for rolling or rocking more or less in the V-channel. 15 For this strip I may use fiber, leatheroid, or other suitable material. The extremities of the V stand out flush with the side of the blade, while the stem thereof supports it in the blade.

20 *O* represents the drill or tool socket, which is threaded onto the lower reduced extremity of the hub of the bowl or crown-shaped gear-wheel *P* in manner to turn therewith. A flange projects laterally from the top of this 25 wheel, on the faces of which are a series of gear-teeth, which mesh with the pinion *K*, through which power is communicated thence to the drill. A spindle *R* is threaded into the pedestal 2 of the body *A* from below, and

30 the hub 9 of the gear-wheel *P* rotates on this spindle and is supported thereon by a head 10 on the lower end of the spindle engaging the reduced extremity 12 of the hub. The thrust of the tool, of course, is upward, so that 35 in operation the friction will be in the same direction. I have therefore provided for keeping the friction down to the minimum by inserting suitable bearings 13 and 14 in the opposed surfaces of pedestal 2 and hub 9 and 40 inserted antifriction-balls 16 therein.

Having reference now again to handle *F* and its supporting-tube *G*, it will be noticed that the tube *G* is a fixed member in socket 45 5 and that an opening *a* in the base of the said socket affords an inlet to the motor-chamber. The opposite end of said tube is fashioned to form a seat for the valve *S*, carried by handle *F*, and a nozzle 17 projects beyond the extremity of the handle *F* and valve 50 *S* to make connection with hose or pipe conducting the motor fluid.

The valve *S* has a series of openings *s*, with a free discharge into the annular space between the valve and the handle *F*, and the 55 said valve also has an enlarged head portion *s'* threaded upon by the handle and affording

the annular space referred to, whence the motive fluid passes into the end of tube *G* when said tube is open. For some distance along its center portion the tube *G* has a quick exterior thread *g*, engaged by a similar thread 60 interiorly on handle *F*, and a packing 20 makes a close engagement between handle and tube at their inner ends and affords freedom for adjustment of the handle on the tube 65 without endangering possible leakage at this point. The valve *S* is controlled by handle *F* and is opened more or less, as may be required. As the handle is always in hand during the use of the machine, the valve is thus 70 easily manipulated according to the needs of the machine, and it can be fully operated without letting go of the handle, which is a great convenience in a machine of this kind.

I have spoken of the pedestal 2 as being at 75 the bottom of the body *A*; but this is more especially for purposes of description, as in use the tool will of course be used in any way most convenient.

In Fig. 5 the chuck 10' for the tool is fixed 80 directly to the motor-shaft 11', and the body 12' has sockets for the handles 13' and 14', as in the other views. A breastplate 15' is employed to bring pressure upon the tool.

What I claim is—

1. In a power-drill, the drill-body and the handles thereon, and a tube in the inlet-handle having a valved passage for the motive fluid, and a valve connected with said handle to open and close said passage, said handle 90 being threaded on said tube and adjustable, substantially as described.

2. A power-drill and its handles, one of said handles comprising a fixed tube with a valve-seat at its outer end, and the handle proper 95 threaded on said tube and a valve connected therewith in position to seat on the end of said tube, substantially as described.

3. In power-drills, the body and the handles thereon, a tube fixed to said body and 100 having the inlet-handle adjustably sleeved thereon and a valve-seat at its outer end, a valve fixed in said inlet-handle to seat on said tube and a nozzle in the extremity of said handle substantially as described.

Witness my hand to the foregoing specification, this 20th day of February, 1899.

CHARLES T. SMITH.
